UNITED STATES PATENT OFFICE

123,573

DESIGN FOR A SEAT OR LIKE ARTICLE

John Gordon Rideout, Cleveland, Ohio, assignor to Calumet Manufacturing Corporation, Hammond, Ind.

Application March 1, 1940, Serial No. 90,613

Term of patent 14 years

To all whom it may concern:

Be it known that I, John Gordon Rideout, a citizen of the United States, residing at Cleveland, in the county of Cuyahoga and State of Ohio, have invented a new, original, and ornamental Design for a Seat or Like Article, of which the following is a specification, reference being had to the accompanying drawing, forming part thereof.

Fig. 1 is a perspective view of a seat or like article showing my new design.

Fig. 2 is a slightly enlarged sectional view taken on line 2—2 of Fig. 1.

Fig. 3 is a slightly enlarged sectional view taken on line 3—3 of Fig. 1.

I claim:

The ornamental design for a seat or like article, substantially as shown.

JOHN GORDON RIDEOUT.
